UNITED STATES PATENT OFFICE.

ERWIN M. JENNINGS AND CHARLES F. MOSMAN, OF BRIDGEPORT,
CONNECTICUT.

DESIGN FOR A CLOCK-CASE.

SPECIFICATION forming part of Design No. 30,985, dated June 13, 1899.

Application filed May 17, 1899. Serial No. 717,222. Term of patent 7 years.

To all whom it may concern:

Be it known that we, ERWIN M. JENNINGS and CHARLES F. MOSMAN, citizens of the United States, and residents of Bridgeport, in the county of Fairfield and State of Connecticut, have invented and produced a new and original Design for Clock-Cases, of which the following is a specification, reference being had to the accompanying drawings, forming part thereof.

Figure 1 is a front elevation of a clock-case embodying our new design, and Fig. 2 is a side view of the same.

As shown in the drawings, the leading or material features of our design consist in a clock-case resembling in general outline a vase, the main body *a* of which is of substantially cylindrical shape and having a central opening *b* and an oval convex-ribbed periphery *c*. Upon either side are attached suitable handles *d*, having scroll and bead ornamentations. A wreath of leaves and berries *e* of

attractive appearance, together with an ornamented base *f*, surmounts the main body. This main body is mounted upon an attractive flaring support *g*, containing ornamental oval medallions *h*, annular convex ribs *i*, and feet *j*, also having medallion and beaded ornaments.

It will be apparent that this design can also be used for other purposes than that stated.

Having thus described our invention, what we claim, and desire to secure by Letters Patent, is—

The design for a clock-case, herein shown and described.

Signed at Bridgeport, Fairfield county, Connecticut, this 13th day of May, 1899.

ERWIN M. JENNINGS.
CHARLES F. MOSMAN.
